UNITED STATES PATENT OFFICE.

RALPH E. RORABECK, OF LAVINA, MONTANA.

FILM-DRYING RACK.

1,051,518.

Specification of Letters Patent. Patented Jan. 28, 1913.

Application filed August 19, 1912. Serial No. 715,853.

To all whom it may concern:

Be it known that I, RALPH E. RORABECK, a citizen of the United States, residing at Lavina, in the county of Musselshell and 5 State of Montana, have invented certain new and useful Improvements in Film-Drying Racks, of which the following is a specification, reference being had to the accompanying drawings.

10 This invention relates to improvements in racks for drying films, and an object thereof is the provision of a rack in which a plurality of films of different sizes may be supported at the same time.

15 A further object of the invention is the provision of a rack in which clamps are vertically adjustable thereon whereby films of different lengths may be secured in the rack.

20 With these and other objects in view, my invention resides in the novel constructions and arrangements of parts to be hereinafter more fully described, claimed, and illustrated in the accompanying drawings, in 25 which—

Figure 1 is a side elevation of my device. Fig. 2 is a section taken on the line 2—2 of Fig. 1. Fig. 3 is a section taken on the line 3—3 of Fig. 1. Fig. 4 is a section taken 30 on the line 4—4 of Fig. 1. Fig. 5 is a section taken on the line 5—5 of Fig. 1, and Fig. 6 is a perspective view of one of the crossed levers and the buffer.

Like characters of reference designate corresponding parts in the drawing.

Referring more particularly to the drawings, the numeral 1 designates generally my improved rack comprising side bars 2, an upper bar 3 and lower bar 4, which are connected to the side bars. Extending downwardly from the ends and the intermediate portion of the frame are rigidly connected legs 5 and pivotally mounted on a rod 6, which is connected to the lower bar 4 of 40 the frame, are legs 7 which are adapted to be folded against the legs 5 when the frame is not in use. Pins 8 are secured to the frame above the pivoted legs 7 to provide stops therefor to limit the upward movement 45 of the legs. Disposed between the end bars 2 are parallel bars 9, which are connected at the upper and lower ends to the upper and lower bars of the frame. These bars are provided on their opposite faces with 50 centrally disposed longitudinal grooves 10 which extend from their upper ends to a

point near the lower bar 4 of the frame. Slidably mounted in the grooves between the parallel bars 9 are clamp members 11, which are formed in two sections 12 and 13. 60 The lower section 12 of the clamping members are relatively longer than the upper section 13 thereof and are adapted to slide in the longitudinal grooves 10 of the bars 9, while the upper sections 13 of the clamp 65 members are adapted to fit flush between the bars, thereby allowing the clamping members to be easily separated. The members 12 and 13 of the clamps are connected at their upper edges by hinges 14 and the 70 upper members 13 are provided with a longitudinal series of pins 15 which are adapted to enter recesses 16 in the lower bar to provide positive means for holding the film within the clamps. Mounted on the rear 75 edge of the lower section 12 is a U-shaped spring member 12' which is adapted to bear against the upper member 13 of the clamp, thereby normally holding the sections in closed position. 80

Secured to the bottom face of the section 12 of the clamps are pivotal crossed levers 17, the upper ends of which are curved to form handles 18, and the lower ends of the levers are adapted to extend below the 85 clamps 11 and have secured on their outer edges buffers 19, which are adapted to engage the parallel bars 9. The buffers are normally held in engagement with the parallel bars by means of an expansion spring 90 20 which is disposed between the handles 18 of the levers.

To facilitate insertion of the clamp members 11 in the grooves 10 of the parallel bars, notches 21 are formed in the upper 95 face of the bars 9 near the lower ends thereof and extend to the grooves 10, whereby the clamps 11 may be readily applied to or removed from the frame when desired. On the lower bar 4 of the frame between the 100 parallel bars 9, are clamping bars 22 which are hingedly connected as at 23, to the bar 4. The bars 22 are provided at their upper edges with a longitudinal series of teeth 24 which are adapted to engage a series of recesses 25 in the bar 4 whereby the lower edge of the film may be securely held in the frame. The clamping bars 22 are normally held in engagement with the bar 4 of the frame by means of U-shaped springs 26 105 110 which are secured to the outer edge of the bar 4 and extend over the clamping bars

22, thereby normally holding the clamping bars in closed position.

The operation of my rack is as follows: In the practical use of my device, the upper section 13 of the clamp 11 may be raised and the upper edge of the film inserted between the members, whereupon the member 13 may be allowed to close and the film will be securely held in the clamp 11 by pins 15, 10 which pierce the film and engage the recesses 16 of the lower section 12 of the clamps. The buffers 19 may then be disengaged from the parallel bars 9 of the frame by movement of the handles 18 of the 15 crossed levers, whereupon the clamps 11 may be moved downwardly upon the frame so the lower edge of the film, may be secured by the clamps 22 to the lower bar 4 of the frame. The film will be securely held 20 to the lower bar 4 by means of pins in the bar 22 engaging with the recesses in the bar 4 and extending through the film. When the film is securely held at its upper and lower ends in the above manner, the clamps 25 11 are then moved upwardly in the frame until the film is extended to its full length, whereupon the handles 18 of the cross levers may be released and the buffers 19 engaged with the side bars 9 whereby the clamps 11 30 are held in adjusted position in the frame.

From the above description taken in connection with the accompanying drawings, it will be seen that I have provided a film drying rack which is simple in construction, 35 which may be easily operated and which is suitable for the reception of a plurality of films of different sizes.

While the accompanying drawings illustrate the preferred embodiment of my invention, minor changes in the construction of the parts thereof may be made, within the scope of the appended claims, without departing from the spirit of my invention or sacrificing any of the advantages thereof.

45 What I claim is:

1. In a rack for drying films, a frame, clamps slidably mounted in said frame, said clamps being formed in two sections and hingedly secured together, means for securing one end of the film between the sections, and means for holding said sections in closed position.

2. In a device of the character described, comprising a frame, clamps slidably adjustable in said frame, said clamps being formed in two sections hingedly secured together, one of said sections being provided with a series of pins and the other section with a series of recesses for the reception of 55 said pins, and means for holding said sections in closed position.

3. In a device of the character described, comprising a frame having spaced parallel bars secured therein, said bars having centrally disposed longitudinal grooves, clamps

slidably adjustable in said grooves, and means for holding said clamps in adjusted position.

4. In a device of the character described, a frame having spaced parallel bars, said bars being provided with longitudinal grooves, clamps slidably mounted in the grooves in said bars, the said bars comprising two sections hingedly secured together, pins carried by one of said sections and adapted to engage recesses in the other of said sections, means for holding said sections in closed position, and means for holding said clamps in adjusted position in said frame. 70 75

5. In a rack for drying films, comprising a frame, spaced parallel bars secured in said frame, the said bars being provided with longitudinal grooves therein, clamps slidably mounted in said grooves, the said clamps being formed in two sections hingedly secured together, means for securing one end of the film between the sections, and means for holding said sections in closed position. 80 85

6. In a rack for drying films, a frame comprising a lower bar, an upper bar, and end bars, spaced parallel bars mounted in said frame between the said end bars, clamping means secured on the said lower bars between said parallel bars, the said parallel bars being formed with longitudinal grooves therein, clamping members slidably mounted in said grooves, said clamping members comprising two sections hingedly connected together, means for securing one end of the film between said sections, and means for holding said clamps in adjusted position. 90 95

7. In a rack for drying films, comprising a frame, clamps secured to the lower end of said frame, parallel bars having longitudinal grooves therein secured in said frame, clamps slidably mounted in said grooves, the said second clamps comprising sections hingedly secured together, crossed levers pivotally secured to the said second mentioned clamps, buffers secured on one end of said levers, the said buffers adapted to engage the said parallel bars for holding the said slideable clamps in adjusted position. 100 110

8. In a rack for drying films, comprising a frame, clamps slidably mounted in said frame, said clamps comprising sections hingedly secured together, means for securing one end of the film between the sections, a spring for holding said sections in closed position, one end of said spring being secured to one edge of one of the sections and bearing against the face of the other of said sections, and means for holding said sections in adjusted position. 115 120

9. In a device of the character described, comprising a frame, clamps slidably mounted in said frame, said clamps comprising sections hingedly secured together, one of 125 130

said sections being provided with a series of pins and the other of said sections having a series of recesses for the reception of said pins, means for holding said sections in closed position, and spring actuated levers for holding said clamps in adjusted position in said frame.

In testimony whereof I hereunto affix my signature in the presence of two witnesses.

RALPH E. RORABECK.
